United States Patent Office

Des. 206,975

Patented Feb. 14, 1967

206,975

TRAFFIC CONE

Robert E. Dawson, Huntingdon Valley, Pa., assignor to
R. E. Dietz Company, Syracuse, N.Y., a corporation of
New York

Filed Jan. 6, 1966, Ser. No. 491

Term of patent 14 years

(Cl. D72—1)

FIG. 1

FIG. 2

FIG. 3

FIGURE 1 is a top plan view of a traffic cone embodying my new design;

FIGURE 2 is side elevational view thereof; and

FIGURE 3 is a bottom plan view thereof.

I claim:

The ornamental design for a traffic cone, as shown.
